UNITED STATES PATENT OFFICE.

WILLIAM E. TRAVERS, OF OAKLAND, CALIFORNIA, ASSIGNOR OF ONE-FOURTH TO
FRANK E. REYNOLDS, OF PIEDMONT, CALIFORNIA.

STEAM GENERATOR.

Application filed May 13, 1922. Serial No. 560,801.

To all whom it may concern:

Be it known that I, WILLIAM E. TRAVERS, a citizen of the United States, residing at Oakland, county of Alameda, and State of California, have invented new and useful Improvements in Steam Generators, of which the following is a specification.

This invention relates to steam generators of the water tube type, and especially to a 10 sectional generator adapted for portable use as in steam driven automobiles and the like.

The object of the present invention is to generally improve and simplify generators of the character described; to provide a generator 15 consisting of a series of parallel sections alternately inclined in opposite directions and each section consisting of a series of superposed interspaced tubes supported between headers and welded thereto to form 20 integral sections; to provide a frame for the reception and support of the section and which frame permits elongation or expansion of the individual sections independently of each other and the frame; to provide a 25 combined steam and water drum and a flexible and expansible connection between each section and a common return communicating with the drum. Further objects will herein-after appear.

30 One form which my invention may assume is exemplified in the following description and illustrated in the accompanying drawings, in which—

Fig. 1 is a perspective view of the generator showing a number of sections removed.

Fig. 2 is a detail view of a portion of one end of one section.

Fig. 3 is an end view of the generator.

40 Fig. 4 is a detail view of the combined water and steam drum showing the steam outlet pipe.

Fig. 5 is an end view of the super-heater employed.

45 Referring to the drawings in detail, and particularly to Figs. 1 and 3, a sectional type of water tube generator or boiler is shown, which consists of a plurality of sections of water tubes A and B alternately inclined in 50 opposite directions and placed side by side. The lower ends of the sections are connected with water drums 2 and 3 and these drums are in turn connected with a combined water and steam drum C by means of a down-flow 55 pipe 4 and an intermediate connection 5.

The upper ends of the sections are connected through expansible, flexible copper tubes 6 with return-flow pipes 7 and 8 disposed on each side of the drum C, and these are in turn connected with a delivery pipe 9 60 which communicates with one end of the drum. The space below the sections consists of a fire-box D, and disposed in the lower portion thereof is a burner E of suitable construction which directs the flame 65 upwardly between the tubes.

The present invention involves several important features; the main purpose of the invention being to provide a boiler or generator which is particularly adapted for 70 portable use as in steam automobiles, tractors and the like. To this end it is obvious that steam must be quickly generated and that the tubes and the remaining structure will be subjected to rapid expansion and contraction, and that such expansion and contraction must be permitted without straining the structure or the connections in any manner. The several sections indicated at 75 A and B are supported by an angle iron frame, consisting of vertical legs 10, horizontal bars 11 and cross or connecting bars 12. The combined steam and water drum is centrally disposed between the frame sections and is supported by the cross bars 12. 80 The individual tubular sections of the boiler are similarly supported by the frame and expansion and contraction of the tubular sections is permitted without in any way transferring strain to the frame or the connections formed between the sections and the 85 drum C.

The construction of the individual sections also forms an important feature of the present invention. For instance by referring to 90 Figs. 2 and 3, it will be seen that each section consists of a pair of header tubes as shown at 14 and 15. The tube 15 is connected through a union 16 with the lower drum 3. The upper end of the header tube 100 15 is bent, as at 17, and it is then extended over to the opposite header tube 14, to which it is welded, as at 18. The header tube 14 is connected through a union 19 with a U-shaped copper tube 6, which in turn is 105 connected through a union 20 with the pipe 7. This connection is expansible and flexible and will function as hereinafter described. The lower end of the header tube 14 is bent, as at 21, and it is then extended over to the 110

2
opposite header tube 15, to which it is welded as at 22. The lower end of the header tube 14 therefore forms the lowermost tube of a section, while the upper end of the header tube 15 forms the uppermost tube of a section. A series of tubes is then introduced between the upper tube 18 and the lower tube 22, and these tubes are welded to the respective headers as shown. In the present 10 instance it will be seen that nine tubes are employed in each section and that two of these tubes are formed as an integral part of the header tubes 14 and 15. The welding of the several tubes with relation to each 15 other forms an integral structure and as the tubes are fairly long, it can be seen that endwise expansion must be taken care of when the boiler is rapidly heating. Such endwise expansion or elongation of the individual sections is provided, due to the flexible tube connection 6 shown, and also due to the fact that the upper bars 11 of the supporting frame are slotted, as at 23, to receive the header tubes 14 of the respective 25 sections. They are thus freely movable in the slots and elongation or contraction can take place without transferring any strain to the frame or any connected part.

By referring to Fig. 3 it will be seen that 30 a small hole is formed in the nipple, which forms a connection between the lower ends of the header tubes 15 and the drums 2 and 3. This is illustrated at 24 and is of considerable importance as it prevents foaming 35 in the drum C, that is the water contained in the drum C is permitted to flow freely through the down-flow tube 4 and through the cross tube 5 into the drums 2 and 3, but upward flow through the header tubes 15 is to a certain extent restricted by 40 the size of the communicating openings 24. This restriction is such that the water entering will all turn into steam before it 45 discharges through the upper ends of the headers 14, the connection 6 and pipe 7 into the drum, and foaming is in this manner prevented; that is the area presented by the tubes in each section is so great that the water admitted through the openings 24 50 will all be evaporated before it can discharge or return to the drum.

The steam delivered to the drum is discharged through the pipe indicated at 25, see Figs. 4 and 5; it then passes through a 55 throttle 26 of suitable construction, and is then directed into a super-heater section generally indicated at 27. This section consists of a pair of headers 28 and 29 and horizontally disposed connection tubes 30. 60 The headers 28 and 29 and the tubes 30 are all welded with relation to each other and an integral structure is here again formed. The discharging steam passes through these tubes and as a large area is presented, any 65 degree of heat may be imparted to the steam

to superheat the same before it finally discharges through the pipe 31, which directs the steam to the engine or other unit driven thereby. The superheating section may be placed at either end of the drum, but preferably at a point where it can be arranged to greatest advantage with relation to the burner E, this being in most instances at the rear end of the generator.

By again referring to Figs. 2 and 3, it 75 will be seen that the header tubes 14 and 15 are provided with extensions 40 and that these are normally closed by screw plugs 41. This is an important feature as removal of the plugs at the opposite ends of the respective tubes permits insertion of wire brushes, cleaning rods and the like, and each section may be readily cleaned from time to time.

Another important feature of the present 85 invention is the provision of individual sections which may be readily removed without interfering with the remaining sections, that is each section is held in place by the unions 16 and 19. These unions when 90 uncoupled entirely release a section and it may be thus entirely removed and replaced by a new section, or the unions 16 and 19 may be temporarily closed if it is desired 95 to continue the operation of the boiler. The tubes in each section, as shown in Fig. 3, are alternately inclined in opposite directions. They are disposed directly above the fire-box D and as such present a mass of 100 tubing which materially restricts the escape of the flame or the products of combustion. This is also of importance as it prevents the free escape of the heat, or in other words baffles the escaping gases to such an extent as to absorb all the heat thereof before it can finally discharge. The inclining of the tubes as shown furthermore tends to 105 spread the upwardly rising gases and uniform heating of the tubes from end to end is thus obtained. The water may be introduced to the boiler by a feed pump, injector or any other suitable means, but as this forms no part of the present invention it 110 is not illustrated. Gauges indicating pressure, and gauges for the purpose of indicating water level may be employed if desired. In the present instance an overflow tube 50 is employed. This tube is provided with a pet-cock at its lower end and it is opened when the generator is being filled with 115 water. The water will in this manner overflow or discharge through the tube 50 when the sections have been filled and the level in the drum reaches the pipe 9, thus indicating that the boiler has been filled. The pet-cock may then be closed and the fire started.

The injector or feed pump employed will then automatically take care of the generator and the operation thereof will be automatic.

While certain features of the present invention are more or less specifically illustrated, I wish it understood that various changes in form and proportion may be resorted to within the scope of the appended claims, similarly that the materials and finish of the several parts employed may be such as the experience and judgment of the manufacturer may dictate or various uses may demand.

It should also be understood that the sections are identical in construction and as such are interchangeable and reversible; this being of further importance as it eliminates the manufacture of so-called right and left hand sections.

Having thus described my invention, what I claim and desire to secure by Letters Patent is—

- 20 1. In a water tube generator of the character described, a water tube section comprising a pair of header tubes, the lower end of one header being bent, extended and connected with the lower end of the other header and the upper end of the last named header being bent, extended and connected with the upper end of the first named header, said extended header tubes forming the upper and lower tubes of a section, and 30 a plurality of tubes interposed between said tubes and connected at their respective ends to the header tubes.
2. In a water tube generator of the character described, a water tube section comprising a pair of header tubes, the lower end of one header being bent, extended and welded to the lower end of the other header, and the upper end of the last named header being bent, extended and welded to the 40 upper end of the first named header, said extended header tubes forming the upper and lower tubes of a section, and said tubes being inclined with relation to the respective header tubes, and a plurality of inclined tubes interposed between said upper and lower tubes and welded at their respective ends to the header tubes.
3. A water tube generator of the character described comprising a pair of side frames, a combined steam and water drum longitudinally and centrally disposed in said frame, a plurality of tube sections disposed below the drum, the tubes in each section being inclined and each alternate section being 55 inclined in an opposite direction, a pair of

water drums disposed in parallelism with the first named drum and arranged below the tube sections and connected therewith, a steam inlet pipe disposed on each side of the first named drum, said pipes being connected and communicating with the interior of the drum, a flexible, expansible connection between each water tube section and the respective steam pipes, and a guide in the main frame engaging the upper end of each water tube section, said guides maintaining a fixed spacing between the water tube sections and permitting free endwise expansion of each water tube section.

4. In a generator of the character described a pair of side frames, an upper bar on each side frame, a series of interspaced slots formed therein, and oppositely inclined water tube sections interspaced and guided thereby.

5. In a generator of the character described, the combination with the lower water drums, the combined steam and water drum, and the frame supporting the same, of a plurality of water tube sections interposed between the lower water drums and the upper combined steam and water drum, said sections being alternately inclined in opposite directions, and the upper end of each section extending through the frame and said frame being slotted to permit the sections to extend therethrough, whereby a spacing is maintained between the sections and free endwise expansion is permitted.

6. In a generator of the character described, the combination with the lower water drums, the combined steam and water drum, and the frame supporting the same, of a plurality of water tube sections interposed between the lower water drums and the upper combined steam and water drum, said sections being alternately inclined in opposite directions, and the upper end of each section extending through the frame and said frame being slotted to permit the sections to extend therethrough, whereby a spacing is maintained between the sections and free endwise expansion is permitted; a steam inlet pipe on each side of the combined inlet and water drum and communicating with the interior of said drum, and an expansible connection formed between the upper end of each section and the respective steam inlet pipes.

WILLIAM E. TRAVERS.
